UNITED STATES PATENT OFFICE

GOTTHARD BAURIEDEL AND AUGUST HARTMANN, OF BARMEN, GERMANY, ASSIGNEES
TO THE FIRM: AMERICAN BEMBERG CORPORATION, OF NEW YORK, N. Y.

MACHINE FOR SPINNING ARTIFICIAL SILK

Application filed September 17, 1928, Serial No. 306,518, and in Germany September 21, 1927.

This invention relates to improvements in machines for spinning artificial silk, and particularly to those employing centrifuges and intended for carrying out the cuprammonium 5 stretch spinning process.

In those machines which are usually employed for carrying out the viscose spinning process, the spinning devices and spinning baths are arranged in front of the machine, 10 whilst a driven drawing roller, to convey the threads further and to introduce them into the spinning centrifuges disposed vertically below and behind the spinning baths, is disposed obliquely above the spinning devices 15 and baths. This arrangement has been approved of in the viscose process and is employed to the greatest extent. A machine having its individual parts arranged in a similar manner and employing centrifuges, but 20 adapted to carry out the cuprammonium stretch spinning process, has, however, proved to be unsuitable and is also difficult to attend to. If now the so-called spinning funnels, which in the present case serve as the spinning 25 devices, and which are of a considerable size, are disposed right at the front of the machine, it is difficult or practically impossible to handle freely the spinning centrifuges disposed behind, and it is also difficult to gain 30 access to the acidifying devices and drawing-off devices which of necessity lie between the spinning devices and the centrifuges. Free access, however, to the machine is indispensable for attending to the machine, that is for 35 the introduction of the thread into and for exchanging the full centrifuges. The machine can be attended to more easily if the centrifuges are placed obliquely below the spinning apparatus. The handling of the 40 spinning funnels is then, however, difficult, and moreover a uniform drawing-off of the threads cannot be effected by maintaining the usual drawing-off arrangements.

The object of the present invention is to 45 provide a machine which is suitable for the requirements above-mentioned.

According to the present invention, a machine for spinning artificial silk by the cuprammonium stretch spinning process and 50 employing centrifuges is provided with spin-

ning devices arranged in an easily accessible manner on one side of the machine, whilst the rollers for guiding, drawing-off and stretching the threads and the spinning centrifuges are disposed on the other side. The threads 55 are thus conducted from one side of the machine to the other. The usual acidifying devices may be disposed between the spinning devices and the centrifuges, as well as a pair of drawing-off rollers which give the required 60 direction of travel to the threads. Both of these rollers may be allowed to run at once at the same peripheral speed in order to ensure that the thread is both drawn off uniformly and against an increased tension. 65 The roller which actually guides the thread to the centrifuge may, however, also be allowed to run more quickly than the first roller in order to give a further additional stretching to the thread on its way from the first to 70 the second rollers. The rollers may also be arranged at an angle to one another so that the machine may be constructed more compactly, and in this manner the stretching of 75 the thread in a transverse direction is reduced. A guiding device may be disposed below the spinning apparatus in order to conduct the thread into an acid bath from which the thread passes on to the drawing-off and stretching rollers, the latter being adapted to 80 conduct the thread in a substantially vertical direction into the centre of the centrifuge lying below. If desired, the first drawing-off roller may rotate directly in the acid bath.

One form of construction is illustrated by 85 way of example in the accompanying drawing wherein the figure shows diagrammatically in end elevation the most important individual parts of a machine in accordance with the invention.

The freshly spun thread is conducted from the spinning apparatus 1 to the guide rod 2 and then passes to the acid bath 3. It is then seized by the drawing-off roller 4 which imparts to it the necessary tension for stretching. The thread is then led further over the drawing roller 5 disposed above and which conducts it further, or again tensions and stretches it, the roller 5 being so arranged that the thread is conducted vertically 100

through the leading-in funnel 6 on the spinning centrifuge 7. The rollers 4 and 5 are driven at an adjustable speed. The fact that the axis of the roller 5 is arranged vertically to the axis of the roller 4 avoids the necessity to arrange the centrifuges farther outside a distance equal to the diameter of the roller 5. In the ordinary way, after leaving the acid bath 3, the stretching of the threads is completed. If, however, the threads are plastic enough, the stretching may be also still continued behind the roller 4, and for this purpose the rollers 5 would be allowed to run faster than the rollers 4.

15 The advantage of the machine constructed in accordance with the invention consists in the fact that it presents easy accessibility to the important individual parts. The spinning apparatus may be observed and attended to easily on the one side, while the spinning centrifuges and their driving devices are also particularly easy of access on the other side. The handling of the drawing-off rollers is also facilitated as well as the imposing of the threads on and cleaning of the rollers.

20 It will be seen that in the drawing an end view of the spinning frame or machine is disclosed. Throughout the length of the machine or frame a plurality of spinning units 25 identical to the one shown, are placed.

Having thus described our said invention, what we claim as new and desire to secure by Letters Patent is:—

25 A machine for spinning artificial silk by the cuprammonium stretch-spinning process, comprising a spinning frame having spinning apparatus arranged on one side thereof, a leading and draw-off roller, a leading and stretching roller, and a collecting means associated with said spinning apparatus, and positioned on the side of the said spinning frame opposite to that side where said spinning apparatus is positioned, said two rollers being arranged one above the other in a vertical 40 plane parallel to the length of the said spinning frame, and adapted to rotate in planes perpendicular to one another.

45 In testimony whereof we have affixed our signatures.

50 GOTTHARD BAURIEDEL.
AUGUST HARTMANN.
